UNITED STATES PATENT OFFICE.

JOSEPH A. NOBLE, OF FOSTORIA, OHIO.

BUILDING-BLOCK.

SPECIFICATION forming part of Letters Patent No. 767,494, dated August 16, 1904.
Application filed December 15, 1903. Serial No. 185,278. (No model.)

To all whom it may concern:

Be it known that I, JOSEPH A. NOBLE, a citizen of the United States, residing at Fostoria, in the county of Seneca and State of Ohio, have invented new and useful Improvements in Building-Blocks, of which the following is a specification.

This invention relates particularly to building-blocks used in wall construction, and has for its object to provide an improved block of the kind stated characterized particularly by an improved arrangement and construction of air-cells and recesses therein. These cells pass only partly through the block, leaving a continuous top or bottom to receive and support the mortar used in binding the blocks together. The air-cells insure dryness in the wall and lightness in the block without impairing the strength of the wall and without producing the weakened joints incident to hollow blocks in which the openings pass all the way through vertically, which gives very little binding surface for the mortar. The block shown and described herein is suitable for all uses of wall construction, foundations, and abutments.

In the accompanying drawings, Figure 1 is a perspective view of the block, showing the bottom thereof. Fig. 2 is a perspective view, partly in longitudinal section. Fig. 3 is a perspective view showing a portion of a wall, with a doorway, constructed of the blocks.

The blocks are made of plastic material, such as concrete or cement, and are preferably made rectangular. The face thereof may be plain or ornamental and the preferable symmetrical construction makes them reversible, so that they may be placed in the wall with the cells up or down. Preferably the cells are placed to open down, and in the description the face through which the cells open is called the "bottom."

Referring specifically to the drawings, the block is indicated at 6 and the cells therein

at 7. These cells are preferably octagonal or circular in shape and are disposed in two parallel rows, as clearly shown in Fig. 1, producing a continuous wall 8, extending lengthwise therebetween. The cells of the respective rows are staggered or placed in zigzag relation to each other, which is believed to produce a stronger construction than if they were placed at right angles to each other. The double row of cells enables the block to be made wide enough so that one thickness will do for an ordinary wall, as shown in Fig. 3. The top 9 of the block is flat and continuous, inasmuch as the cells 7 do not extend all the way through. In both ends of the block are recesses 10, which extend from the bottom of the block nearly to the top thereof and are useful for various purposes. They admit of slight tooling to cut away the remaining portion 11 to receive door or window casing, cleat, or strip, as indicated at 12, which is thus sunk into the ends of the blocks when the same are used in wall construction, forming with mortar a practical air-tight joint. The recesses 10 also form places for hand-holds in lifting and setting the blocks. Also when set up in the wall the mortar placed between the ends of the blocks engages behind the side edges of the recess, forming an effective end bond.

In use in building the mortar is conveniently and easily spread on the plain top surface of the blocks, and they may be laid by any ordinary stone or brick mason. When the following course is placed on the lower course, the mortar on the top of the blocks presses up into the cells, making the same air-tight and also forming a substantial bond, preventing movement of the blocks upon each other and forming a wall of great strength and solidity without the assistance of any metal or other binding device. In this respect it is especially serviceable for abutments, retaining-walls, and docks. The cells

become air and water tight and a dry, light, and cheap construction is produced.

What I claim as new, and desire to secure by Letters Patent, is—

5 A building-block having a flat continuous top the full size of the block, a series of cells in the bottom, arranged in two parallel rows and zigzag relation to each other, and a recess in each end of the block, open at the bot-

tom and having thin walls at top and side, removable to receive a frame.

In testimony whereof I have signed my name to this specification in the presence of two subscribing witnesses.

JOSIAH A. NOBLE.
